Int. Cl. D24—99

U.S. Cl. D83—1 E

*FIG. 6.*FIG. 1 is a perspective view of a litter embodying my new design. FIG. 1 shows primarily the underside of the litter;

FIG. 2 is a top plan view of the litter;

FIG. 3 is a side elevational view of the litter showing the side of the litter which is hidden in FIG. 1;

FIG. 4 is a rear elevational view taken from the bottom of FIG. 2;

FIG. 5 is a front elevational view taken from the top of FIG. 2; and

FIG. 6 is a sectional view taken along line 6-6 of FIG. 2.

I claim:

The ornamental design for a litter, substantially as shown.
